(57) **CLAIM**

The ornamental design for a medical device for peristaltic pump, as shown and described.

DESCRIPTION

FIG. 1 is a first perspective view of the medical device for peristaltic pump;

FIG. 2 is a second perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

Portions of the article shown in broken lines form no part of the claimed design.
